UNITED STATES PATENT OFFICE.

THEODORE SMOLINSKY, OF GARY, INDIANA.

TOY HAMMER.

1,359,927.

Specification of Letters Patent. Patented Nov. 23, 1920.

Application filed April 29, 1920. Serial No. 377,515.

To all whom it may concern:

Be it known that I, THEODORE SMOLINSKY, a citizen of the Republic of Austria, and a resident of Gary, in the county of Lake and State of Indiana, have invented certain new and useful Improvements in Toy Hammers, of which the following is a specification.

My invention relates to toy hammers, and has for its primary object the provision of novel means for operating the head of a hammer with relation to a fixed anvil. A further object lies in the provision of an improved form of crank for operation of the hammer, said crank being exceedingly simple in form and cheap to manufacture.

Other objects and advantages of the invention will appear from the following description, taken in conjunction with the accompanying drawings which form a part of this specification and illustrate the preferred embodiment of the invention.

In the drawings:

Figure 1 is a top plan view of the invention.

Fig. 2 is a front elevation thereof.

Fig. 3 is a detached perspective view of the crank forming part of the present invention.

The main frame of my invention comprises right and left spaced uprights 10 and 11 respectively, joined at their tops by a bar 12 and at a point intermediate their ends by a horizontal beam 13. In the lower angle formed by upright 10 and beam 13 is secured a guide block 14, and a similar guide block 15 is oppositely positioned in the lower angle formed between beam 13 and upright 11.

The opposed edges of the guide blocks are vertically channeled as at 16 to receive guide pins 17 which project outwardly in opposite directions from the sides of a vertical movable hammer head 18 adapted to operate upon an anvil 19 fixedly positioned below it. Projecting upwardly from the center of hammer head 18 is a hammer shaft 21 fixed within the hammer head and by means of which the latter is operated. Vertically aligned apertures formed centrally in the bar 12 and the beam 13 form the bearing guides for the shaft 21.

Between bar 12 and beam 13 the shaft 21 is provided with a transverse horizontal pin 22 or any similar element which will present a downwardly exposed shoulder rigid with relation to the shaft and accessible to the upward impulse of an operating crank.

Between the pin 22 and the bar 12 is compressed a helical spring 23 which normally urges the hammer and its shaft downwardly against the anvil 19, as indicated in dotted lines in Fig. 2.

The upper angle formed by upright 10 and beam 13 is spanned by forward and rear braces 24 and 24' respectively, and these braces are oppositely apertured in their central portions to provide bearings for a crank generally indicated at 25.

The crank 25 comprises a single piece of bent heavy wire. This wire is bent as best shown in Figs. 1 and 3 to form a pair of opposite trunnions 26 and 27 which are respectively journaled in the braces 24 and 24' as shown. From these trunnions radial arms 28 extend in diametrically opposed directions and, at their outer ends, are joined by cranks 29 and 31, adapted to alternately engage the pin 22 and the hammer shaft to elevate the latter.

The trunnions 26 and 27 are journaled in the braces 24 and 24' in such position that, when arms 28 are vertical the cranks 29 and 31 are outside of the vertical path of movement of pin 22; but rotation of the element 25 brings cranks 29 and 31 alternately under pin 22 when the latter is in its lowest position as indicated by dotted lines in Fig. 2.

In the operation of the invention, and considering the parts as in the lower dotted line position of Fig. 2, wherein the hammer head 18 is at rest upon the anvil 19, the child operating the toy rotates the crank 25 by means of the operating handle 32. The crank 29 rises beneath pin 22 elevating the latter together with shaft 21 and hammer head 18 upwardly against the pressure of spring 23 into the full line position of Fig. 2. Before crank 29 has reached the zenith of its upper arc it slips out from beneath pin 22 and the pressure of spring 23 augmenting the force of gravity drives the hammer head 18, shaft 21 and pin 22 violently and rapidly downward against the anvil 19. The pressure of spring 23 is such that the hammer head 18 strikes the anvil before crank 31 rises to the level of the bottom of pin 22 when the latter is in the dotted line position of Fig. 2 so that there is no shock to the operator by reason of the downwardly moving pin 22 striking the upwardly rotating crank 31. The crank 31, just after impingement of the hammer head

upon the anvil, rises beneath pin 22 as just above described with respect to crank 29, and the hammer head is again raised and released for descent upon the anvil. By the 5 structure just described I accomplish two strokes of the hammer to one rotation of the cranking element 25. Inherent in my invention is also that extreme simplicity and cheapness of construction which is a 10 desirable feature of every toy.

While I have illustrated the preferred embodiment of my invention, it is obvious that one skilled in the art may make modifications thereof without departing from the 15 spirit of the invention. I wish therefore not to be restricted to the precise embodiment shown, except in so far as same is limited in the appended claim.

I claim:

20 In a toy, the combination of a suitable frame provided intermediate its ends with a cross beam, a guide member disposed at

each side of the center of said frame, said members being attached to said cross beam and the side members of the frame respectively and being provided with guideways, 25 a hammer having laterally extending guiding elements projecting into said guideways, the shaft of said hammer extending through said beam and the upper member of said frame and guided thereby, an abutment member projecting laterally from said shaft, a spring interposed between said member and the top member of the frame, 30 angularly disposed brace members secured to said beam and to the upright members of said frame, and a rectangular actuating device pivoted in said brace members, said device being shaped to provide oppositely disposed actuating portions between said 35 brace members, and an operating handle disposed outside said brace members.

THEODORE SMOLINSKY.
